Primary Examiner — Elizabeth A. Albert(74) *Attorney, Agent, or Firm* — Ohlandt, Greeley,
Ruggiero & Perle, L.L.P.(57) **CLAIM**

The ornamental design for a writing instrument, as shown and described.

DESCRIPTION

FIG. 1 is a front perspective view of an ornamental design for a writing instrument according to the present invention; FIG. 2 is a left side elevational view thereof; FIG. 3 is a right side elevational view thereof; FIG. 4 is a front side elevational view thereof; FIG. 5 is a rear side elevational view thereof; FIG. 6 is a bottom plan view thereof; and, FIG. 7 is a top plan view.

The large curved claimed lines are shown on an entirely unclaimed surface. The broken lines shown in FIGS. 1-7 are for the purpose of illustrating environmental structure and form no part of the claimed design.

1 Claim, 7 Drawing Sheets(56)
